UNITED STATES PATENT OFFICE.

ANNA F. GARRETSON, OF TURNER, OREGON.

STOVEPIPE-CLEANER.

1,361,708.

Specification of Letters Patent. Patented Dec. 7, 1920.

Application filed October 8, 1919. Serial No. 329,396.

To all whom it may concern:

Be it known that I, ANNA F. GARRETSON, citizen of the United States, residing at R. R. #2, Turner, in the county of Marion and State of Oregon, have invented certain new and useful Improvements in Stovepipe-Cleaners, of which the following is a specification.

This present invention relates to improvements in stove pipe and flue cleaners and as its principal object aims to provide a device of this character as is normally carried by the stove pipe and which may be brought into operation quickly and easily and which will thoroughly clean the pipe at the point desired.

The further object of the invention is to provide a device of the above character which is cheap to construct, easy to apply to conventional stove pipes, and one which does not obstruct the stove pipe or in any way prevent the free passage of smoke therethrough. Various other objects and advantages of my invention will become apparent from the contents of the following description.

In the drawings:—

Figure 1 is a view in perspective showing my invention applied to a stove pipe in conventional form.

Fig. 2 is a view in cross section showing my invention applied to the elbow of a stove pipe.

Fig. 3 is a view in top plan of my invention.

Fig. 4 is a view in longitudinal section of cleaner.

Fig. 5 is a detailed view of a handle that may be used to operate the cleaner, and

Fig. 6 is a detailed view of means to normally hold the cleaner in an inoperative position.

To illustrate the particular usages of my invention I have shown in the drawings a stove pipe of conventional form, consisting in part of an elbow 10 which to accommodate the cleaner contemplated by my invention is provided with an opening 11. It is pointed out that the edges of this opening

11 may be turned inwardly at 12 to form a 50 collar or offset portion within the elbow as clearly shown in Fig. 2.

My improved cleaner consists of a body portion 13 which may be constructed of metal, a handle portion 14 which is adapted 55 to slide through the opening 11 of the elbow and a reinforcing plate 15 which secures the handle 14 to the body member 13 as at 16 and 17. Ways 18 are formed in the member 14 having one edge substantially flushed 60 with the outer face of the body member 13 when the latter is in its normal position. When the cleaner is not in use the handle member 14 projects outwardly through the opening 11 of the elbow and the prongs 19 65 of a resilient key 20 fit the ways 18 in order to hold the entire device in a substantial rigid position. The body member 13 and the reinforcing plate 15 being constructed of metal are designed to give slightly when 70 the handle member 14 is drawn outwardly through the opening 11 so that when the key 20 is in place the said body member and reinforcing plate will tend to draw the handle member 14 into the elbow, thus locking 75 the key tightly in place.

I further provide the handle member 14 with a threaded opening 21 so that an extension handle such as shown at 22 may be provided in order to operate the cleaner 80 within the elbow. This handle may be in sections as shown in Fig. 5.

Having thus fully described my invention, what I claim as new, and desire to secure by Letters Patent is:

A stove pipe cleaner comprising in combination, a body member, a handle portion, means yieldingly connecting said body portion and said handle portion, said handle member adapted to normally project 90 through an opening in a stove pipe elbow, said handle portion being provided with ways normally lying on the outside of said stove pipe, and a key fitting said ways to lock said handle portion rigidly to said stove 95 pipe substantially as described.

In testimony whereof I affix my signature.
ANNA F. GARRETSON.
